US00D823241S

(12) **United States Design Patent** (10) Patent No.: **US D823,241 S**
(45) Date of Patent: **** Jul. 17, 2018**

(54) **BATTERY BASE**

(71) Applicant: **SHENZHEN REDARROW TECHNOLOGY CO., LTD.,**
Shenzhen, Guangdong Province (CN)

(72) Inventor: **Zhinan Zhang**, Shenzhen (CN)

(73) Assignee: **SHENZHEN REDARROW TECHNOLOGY CO., LTD.,**
Shenzhen, Guangdong Province (CN)

(**) Term: **15 Years**

(21) Appl. No.: **29/604,901**

(22) Filed: **May 22, 2017**

(51) LOC (11) Cl. **13-02**

(52) U.S. Cl.

USPC **D13/103; D13/108**
